[57] CLAIM

The ornamental design for a portable, battery operated light magnifier apparatus for computer video game, as shown and described.

DESCRIPTION

FIG. 1 is a perspective view of a portable, battery operated light magnifier apparatus for computer video game showing our new design;

FIG. 2 is a perspective view thereof; in an open position;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof;

FIG. 8 is a rear elevational view thereof;

FIG. 9 is a top plan view of FIG. 2;

FIG. 10 is a bottom plan view of FIG. 2;

FIG. 11 is a left side elevational view of FIG. 2;

FIG. 12 is a right side elevational view of FIG. 2;

FIG. 13 is a front elevational view of FIG. 2; and,

FIG. 14 is a rear elevational view of FIG. 2.

The broken line showing of a video game apparatus is for illustrative purposes only and forms no part of the claim.
